VICTOR H. HARBERT, OF CHICAGO, ILLINOIS, ASSIGNOR TO E. PAYSON SMITH, OF SPRINGFIELD, ILLINOIS.

BRAKE-GEAR MOUNTING.

Application filed July 6, 1926. Serial No. 120,570.

My invention relates to mountings or housings for the gear mechanism which operates the brakes of railway cars; the housings being of a construction adapted to be secured to the end of a car either to the car end sill or to the end sill of the car underframe.

The mounting preferably consists of a pair of members so constructed and secured together that sufficient strength and rigidity will be provided; easy assembly of the gear elements permitted and attachment to the car frame or underframe easily accomplished.

The objects and advantages of my invention will be readily comprehended from the detailed description of the accompanying drawings, wherein—

Figure 1 is a top plan view of my improved mounting shown attached to the end sill of a car; only a portion of the end sill and striking casting being shown with the brake-staff shown in section.

Figure 2 illustrates the same in elevation. Figure 3 is a cross sectional view taken on the off-set line 3—3 of Figure 1 looking in the direction of the arrows.

Figure 4 is a perspective view of the top member of the mounting or housing.

Figure 5 is a perspective view of the bottom member of the mounting or housing.

Figure 6 is a side elevation of a modification of my improved housing and the method of mounting the same, namely applied to the end sill of a car underframe and braced from the end sill of the car body.

Figure 7 is a top plan view thereof with portions of the sill of the car body and end sill of the underframe; the latter with the brake-staff being shown in section.

In the exemplification of the invention as illustrated in the first three figures of the drawings; my improved mounting is shown secured to the stiffening member or end sill 10 of a car body and located adjacent to the striking casting, a portion whereof is shown at 11. The mounting comprises a top member 12 and a bottom member 13, the general constructions whereof are more clearly shown in Figures 4 and 5.

The top member 12 consists of a plate which may be substantially rectangular as shown, with the inner end 14 having a substantially flat upper surface to extend flush with the bottom flange of the end sill 10

of the car body to which it is secured by means of rivets 15; the portion 14 of the top plate being apertured at 16 to receive the rivets 15. The inner portion 14 of the top plate, as seen in Figure 3, not only extends flush with the bottom of the end sill of the car body, but also terminates adjacent to the inner end of the lower flange of the end sill member 10. The forward or outer end of the top plate 12 is shown preferably slightly offset or stepped downwardly at 17 in order to provide proper bearing for the short upper trunnion of the drive element or gear 18 which latter is controlled by the brake-staff 19. The forward or outer end of the top plate 12 is apertured at 20 (see Figure 4) to receive the upwardly disposed trunnion 21 of the drive element, see Figure 3; the drive element or gear being provided with a squared opening to receive the squared lower end of the brake-staff 19.

The top of the plate 12 is provided with a transversely disposed upstanding wall 22 reinforced by the outwardly sloping ribs 23 all of which are preferably formed integral with the top plate. The upstanding wall 22 is adapted to extend flush with the outer end of the car, as for example against the steel end or outer sheathing 24, see Figure 3; the upstanding wall 22 being apertured as at 25, 25 to receive the rivets 26, 26 whereby the top plate is also secured to the upstanding leg of the car end-sill and the sheathing.

The forwardly extending portion or outer end of the top plate 12 is also shown provided with a suitable number of bolt or rivet-receiving holes 27 for the reception of the rivets 28 whereby the bottom member or plate 13 is secured thereto.

The bottom member or plate 13 consists of the forward portion 29, of dimensions substantially equal to the width of the forward outer end of top plate 12, see Figure 5. This end 29 of bottom plate 13, which may be substantially rectangular, is provided with upstanding ends 30 and 31 which in turn terminate in the horizontally and inwardly disposed lobes 32, 33 apertured at 32^a and 33^a to register with the apertures 27 in the top plate 12. The inwardly disposed lobes 32, 33 are intended to lie flush with the bottom of the forward end of the top plate 12, to which it is secured by the rivets 28.

The portion 29 of the bottom plate 13 is shown provided with an apertured boss 34 to receive the trunnion 35 on the lower side of the drive element or gear 18 so as not only to provide suitable rotative bearing but also provide a support for the drive element. The lower trunnion 35 of the drive gear is inwardly flanged at 36 to provide a shoulder for the squared portion of the brake-staff 19; while the reduced end 37 of the brake-staff is disposed through the aperture in the boss 34 of the bottom plate and is held against upward removal of a suitable cotter-pin as at 38 in Figure 2.

15 The bottom member or plate 13 at a point intermediate of the ends of the rectangular portion 29, namely at a point in alignment with the apertured boss portion 34, is provided with an inwardly disposed arm 39 which is shown preferably off-set into a lower plane to provide suitable space between the top and bottom members to house the driven element or gear 40 and the chain receiving drum or spool 41. The bottom member is preferably provided with the vertically disposed reenforcing ribs or webs 42 extending throughout the length of the bottom member.

15 The inwardly disposed end 39 of the bottom member is provided with an apertured boss 43 to provide a seat for the drum or spool 41 and to receive the extended hub 44 of the gear 40. The gear and drum or spool are held in place by the pin 45, which also assists in supporting the inner end of the bottom plate 13.

15 The top plate or member 12, on its lower side, is shown provided with a boss 46 apertured to receive the pin 45 and the top surface of the top plate 12 is countersunk at 47 to receive the head of the pin 45. This permits the top plate to extend flush with the bottom of the end sill. The pin 45 may be of any suitable construction; and while displacement of the pin or bolt 45 is impossible after the housing is in place, the lower end of the pin is shown threaded to receive a nut 48 in order to ensure the elements being held in assembled relation before the housing is mounted on the car; namely to prevent loss of the pin before installation.

15 In view of the housing being secured to the end sill of the car body and therefore adjacent to the striking casting 11, the countersunk opening 47 in the top member or plate 12 is shown off-set from the opening 20 and the opening 43 in bottom member 13 off-set from opening 34, in order to provide proper clearance for the large driven element or gear 40, relative to the center sill and striking casting of the car, see Figure 1.

15 In Figures 6 and 7, I show a modification of the invention; the figures illustrating a mounting of the gear mechanism beneath and to the bottom flange of the end sill 49

of the car underframe. The construction of the main portion of the housing is substantially identical with that previously described; the housing consisting of the top plate 50 and bottom plate or member 51 secured together as previously described. The top plate in this construction is preferably tapered at its inner end as shown at 50^a (Figure 7) and is provided with the laterally disposed lobes 52, 52 (see Figure 7) to receive rivets 53 for securing the top plate to the lower flange of the underframe end sill 49. The bottom member or plate 51 in this instance is secured to the top plate by means of four rivets 54; and the top surface of the upper top plate 50 is provided with the upstanding flange or wall 55 disposed transversely of the top plate with the ends of the flange or ribs sloping downwardly toward the outer corners of the forward portion of the top plate 50, see Figure 7. The upstanding flange or wall 55 is intended to extend flush with the outer vertical face of the underframe end sill 49. The mounting also involves a reenforcing brace or strap 56 preferably of the rectangular formation shown in Figure 6, with one end disposed flush with the bottom of the car floor 57; to which, as well as to car end sill 10, it is secured as shown at 58. The other or lower portion or end of the brace plate or strap 56 is riveted to the top plate 50, as shown at 59, and is bent upwardly to lap the lower flange of the underframe end sill 49 as well as to extend flush with the inner vertical face thereof. This last mentioned end of the brace plate or strap 56 is riveted to the underframe end sill 49 by rivets 60 which also secure the upstanding flange or wall 55 of the top plate to the end sill.

105 The lower surface of the top plate is shown provided with a depending stop lug 61 adapted to be engaged by a lug 62 formed on the driven element or gear 40, to prevent improper rotation of the driven element.

110 The constructions shown provide a gear mounting possessing the requisite strength while at the same time being comparatively light in weight; constructions which may be easily assembled and installed on a car.

115 The invention with its modification has been described in terms employed merely as terms of description and not as terms of limitation as structural modifications are possible without, however, departing from the spirit of my invention.

120 What I claim is:

1. Brake gear mounting comprising a top plate, the inner end whereof is adapted to extend flush with the bottom of a car end sill and to be secured thereto, an upstanding wall disposed transversely of the top plate intermediate of its ends and adapted to be secured to the forward outer face of the car 125 130

- end or its end sill, and a bottom plate having upwardly disposed flanges integral with one end of the plate, said flanges terminating in inwardly disposed apertured lobes adapted to extend flush with the bottom of the top plate and to be secured thereto, said bottom plate having an extension disposed inwardly from an intermediate point, the top and bottom plates being each provided with a pair 50 of registering apertures, with the registering apertures at the inner end of the top plate and in the extension of the bottom plate being off-set relative to the centers of the other registering apertures.
- 10 2. In a brake gear mounting, a top plate, the inner end whereof is adapted to extend flush with the bottom of a car end-sill and to be secured thereto, said inner end being provided with a countersunk pin-receiving 55 opening, a transversely disposed upstanding wall intermediate of the ends of the top plate, and a bottom plate, one end whereof is provided with upwardly disposed sides terminating in laterally disposed portions 60 adapted to extend flush with the bottom of the top plate and to be secured thereto, an inwardly disposed extension, intermediate of the sides of the bottom plate, provided with a pin-receiving opening, the outer end 65 of the top plate and of the bottom plate being provided with registering brake-staff receiving openings.
- 15 3. In a brake gear mounting, a top plate, the inner end whereof is adapted to extend flush with the bottom of a car end sill, said end having outwardly disposed lobes on opposite sides for attachment to the end sill, a transversely disposed upstanding wall intermediate of the ends of the top plate terminating in forwardly and outwardly sloping reenforcing ribs, a rectangular shaped strap secured to the inner end of the top plate, one end of the strap being adapted 70 to extend flush with the rear side of the end sill and be secured thereto while the other end extends flush with the car bottom 75
- 20 4. In combination with a car end sill, a gear mounting comprising a top plate adapted to extend flush with the bottom of 80 said sill and to terminate at the inner end with the inwardly disposed lower end of said sill, said top plate having an integral upstanding portion disposed transversely adapted to be secured to the outer side of the end sill, and a bottom plate having upstanding sides at the outer end terminating in horizontally disposed portions adapted to extend flush with the top plate and be secured thereto, both plates being provided 85 with registering openings.
- 25 5. In combination with a car and its underframe end sill, a gear mounting comprising a top plate adapted to extend flush with the bottom of said sill and be secured thereto, a bottom plate having upstanding sides at 90 one end terminating in horizontally disposed portions adapted to be secured to the top plate, and a strap, one end whereof is secured to the top plate and to the inner side of the end sill while the other end extends flush with the car floor and car end sill and is secured thereto.
- 30 6. In combination with a car bottom and the end sill of its underframe, a gear mounting comprising a top plate arranged flush with the bottom of the end sill and secured thereto, a bottom plate having upstanding sides at one end terminating in horizontal lobes adapted to be secured to the top plate, and a three sided strap, one side being secured on the top plate and to the rear side of the end sill while a second side is secured to the car bottom, the third side being disposed upwardly adjacent to the inner end of the top plate.

VICTOR H. HARBERT.
